UNITED STATES PATENT OFFICE

LYLE W. BROWNE, OF MARSHALLTOWN, IOWA, ASSIGNOR TO THE FISHER GOVERNOR COMPANY, INC., OF MARSHALLTOWN, IOWA, A CORPORATION

AUTOMATIC LIQUID EXTRACTOR

Application filed November 25, 1929. Serial No. 409,709.

This invention relates to improvements in automatic fluid extractors for the removal of liquids from a zone of low pressure to a zone of higher pressure.

The primary object of this invention is the provision of an improved vacuum trap or fluid extractor embodying the general characteristics of the trap set forth in U. S. patent application, Serial No. 63,198, filed October 17, 1925, and being improved thereover in the provision of, first, a variable pressure equalizing connection between the trap chamber and the low pressure zone from which it is desired to extract the liquid; second, the provision of an improved pressure control valve; and third, the provision of an improved float mechanism, the leverage of which may be suitably adjusted for efficient operation of the pressure control valve under variable conditions of pressure.

Other objects and advantages of this invention will be apparent during the course of the following detailed description.

In the accompanying drawings, forming a part of this specification, and wherein similar reference characters designate corresponding parts throughout the several views,

Figure 1 is a vertical sectional view taken through the improved vacuum trap.

Figures 2, 3, 4 and 6 are sectional views taken substantially on their respective lines in Figure 1 of the drawings.

Figure 5 is a side view of a valve stem guide and supporting member used with this invention.

Figure 7 is a fragmentary view showing the relation in which the improved fluid extractor is connected with respect to vacuum and discharge connections.

In the drawings, wherein for the purpose of illustration is shown only a preferred embodiment of the invention, the letter A may generally designate the improved automatic liquid extractor, which may be used for the purpose of withdrawing liquid from various apparatus, such as shown in the co-pending application above referred to, and in the present case showing its connection with respect to a tank B wherein a sub-atmospheric pressure exists.

The automatic fluid extractor or trap A includes a casing 10, preferably of cast iron, comprising a bottom 11 having the upstanding walls 12 surrounding the same and provided with a top wall 13. It defines a trap chamber 14 for receiving liquid from an inlet line 15 which connects with the tank B or any other vacuum source. The top wall 12 is provided with a relatively large opening 14^a therein, upon which a cast iron cover 15^a is detachably connected at 16 in any preferred manner. If found necessary suitable gaskets may be provided to insure a leak-proof connection about the opening 14^a. The cover 15^a is provided with a substantially central raised portion 17 having an axial opening 18 extending through the cover, wherein pressure control valve details are adapted to seat, as will be subsequently mentioned. On top of the raised portion 17 an inverted cup-shaped cap 20 is detachably supported and connected to the cover 15^a by bolt means 21 shown in Figure 2 of the drawings. There is provided a pressure compartment 23 which may appropriately be referred to as a pressure chest. The closure 15^a is provided with a duct 25 radially extending therethrough into the pressure chest compartment 23, and the closure 15^a is provided with a screw-threaded opening 26 wherein an actuating pressure line 27 is detachably connected for discharging its contents into the duct 25. This line 27 is adapted to receive air, gas, or steam as the pressure medium, and it is preferably provided with a strainer 28 of any approved type.

The inlet line 15 has connection at 16^a with the bottom of the vacuum tank B and horizontally connects at 30 in one end wall 12 of the casing 10 near the bottom 11 for the purpose of discharging liquid, trapped from the tank B, into the trap compartment 14. A deflector or baffle 31 is preferably cast with the casing 10, extending across the inlet of the line 15 and being spaced slightly from the bottom, as shown in the drawings. The inlet line 15 of course has a check valve structure 33 including a valve 34, pivoted at 35, and permitting liquid to enter the compartment 100.

ment 14 but preventing its reverse flow therefrom.

At the opposite end of the casing 10 from the inlet connection above described, there is provided a discharge line 36, connected at 37; the discharge line 36 having a vertical riser portion 36^a therein for the purpose of creating a liquid seal to prevent infiltration of air into the trap compartment or chamber. This discharge line 36 is provided with a check valve 38, the valve member 39 of which is movably connected at 40 in such relation that liquid is permitted to flow from the chamber 14 and not return thereto.

As has been described in the co-pending application above mentioned, liquid will be permitted to enter the trap compartment from the tank B through the line 15, inasmuch as there is an equalization of pressure in the chambers of the tank B and trap A. However, due to the high pressure existing in the discharge line 36 and the storage source to which the liquid is to be discharged, it is quite apparent that there is no possibility of discharge of the entrapped liquid from the chamber 14 through the discharge line to the storage source until an equal or greater pressure exists in the chamber 14 than the discharge line 36. For the purpose of controlling actuating pressure, novel float actuated valve mechanism E is provided, which permits the greater pressure from the chest 20 to pass into the chamber 14.

Referring to the valve mechanism for regulating inlet of pressure, a hollow valve seat 45 is screw threaded in the passageway 46 of the upper cylindrical extension 47 of a cast iron valve support and guide member 48. The member 48 is provided with an attaching flange 44 which is bolted at 50 to the under side of the cover 15, as shown in Figures 1 and 2 of the drawings; the support 48 being particularly detailed in Figure 5 of the drawings. It includes a depending shank 51 from one side of which horizontally extending valve stem guide arms 52 project, and from the lower end of which a float pivot supporting arm 53 extends in an opposite direction. A pressure controlling valve member 55 is supported on the seat 45, having a depending valve stem assemblage consisting of a pair of valve stem parts 57 in alignment, which are guided through the arm portions 52 of the support, as shown in Figure 2 of the drawings. The valve stem parts 57 between the guide arms 52 detachably support a transversely apertured connection 60, through which a portion of the counterweight means, to be subsequently described, extends to counterbalance the dead weight of the parts of the valve mechanisms and float assemblage.

At its lower end the valve stem portion 57 detachably supports a vertically elongated stirrup 62, having a vertically elongated opening 63 therethrough; the end surfaces

of the stirrup 62 facing the opening 63 being tapered to chisel edges for cooperation with the float arm 64 in a manner to be subsequently mentioned.

The depending shank 51 between the guide arms 52 pivotally supports at 67 a counterbalancing weight. The counterbalancing weight includes a substantially V-shaped arm 70, pivoted between its ends at the connection 67 above mentioned, one end extending slidably through the opening of the valve stem connection 60 above mentioned, the other end extending into an upper corner of the tank chamber for adjustably supporting a weight 72, which may be adjusted on the end of the arm or lever 70 by a set screw 73. It is perfectly apparent that the weight 72 acts normally to unseat the pressure control valve 55, and its purpose is to balance the dead weight of the valve details and in some instances a portion of the float arm mechanism.

Referring to the float for actuating the pressure control valve, the end wall 12 of the casing 10 is provided with a screw threaded opening 80 therein, detachably receiving a tubular extension 81 which projects from the casing 10 and has a detachable cap 82 screw threaded thereon at its outer end. The arm 53 of the supporting device 48 adjacent the wall 12 is provided with a depending shank having a square or other non-circular opening 84 therein, axially aligning with the passageway through the tubular extension 81, wherein an adjustable float supporting member 85 is horizontally slidable. This member 85 is non-rotatable in the opening 84 since, as shown from Figure 6, it has the same cross section as the opening 84. At its end facing the chamber 14 the horizontal shank 85 is provided with a detachable depending connection 87, the lower bifurcated end of which pivotally connects an end of the float arm 64, as at 88. The float arm 64 at its end opposite the pivot 88 is of course provided with a float 90 of any approved character, which may be detachable if found desirable.

It is the purpose in so mounting the float that the pivot 88 thereof may be moved towards or away from the supporting member 62 to increase or decrease the leverage action which the float mechanism has upon the pressure control valve mechanism. In order to effect and maintain the desired adjustment, an adjusting screw 95 is provided, having an outer screw threaded portion 96, which is screw threaded at 97 within a screw threaded opening axially of the cap 82, as shown in Figure 4. A lock nut 98 may be provided on the outer end of the screw threaded portion 96 to lock the screw 95 in the desired adjustment. At its inner end within the tubular extension 81 the screw 95 has another screw threaded portion 100, which is oppo-

sitely screw threaded with respect to the portion 96. As a preferred example of the screw threaded arrangement, it is preferred to make the portion 96 one-half inch in diameter and provide twenty right-hand screw threads to the inch. The portion 100 on the other hand is $\frac{3}{8}$ inch in diameter, and sixteen left hand screw threads are provided to the inch. The adjustable slide 85 is axially provided with a screw threaded passage-way 101 therethrough, wherein the portion 100 of the screw 95 is threaded. A centering stem 104 may be adjustable in a suitable socket provided in the slide 85, as shown in Figure 4.

In order to equalize the pressure in the vacuum tank B and trap chamber A, a connecting line 110 is attached to the upper portion of the tank B and to the top of the casing 10, as shown in Figure 1. This balance of pressure permits the liquid to readily enter the trap chamber 14. In order to vary the effective communication between the trap A and tank B through the line 100, a globe valve 112 has been provided, which will enable a variable communication to be established, according to conditions which require that the communication be accurately adjusted.

With reference to the general operation of the improved device, assuming that a balanced pressure exists in the trap A and tank B, the liquid enters through the line 15 and is prevented from passing the check valve 39 due to the low pressure in the trap chamber 14 and a higher pressure in the discharge line 36. As the liquid rises in the chamber 14 the float 90 rises, and when a proper amount of liquid has entered the trap chamber 14 the pressure actuating the float 90 will cause a lifting of the valve 55. The force required to do this does not necessarily have to be great, inasmuch as the valve details are either entirely or partially balanced by the counterweight. Lifting of the valve 55 permits pressure, which has entered the chest 20 through the pressure line 27, to enter the trap chamber 14, shutting the check valve 34 and opening the check valve 39 and forcing or permitting the liquid to drain from the trap 14 through the discharge line 36. The falling of the float arm 64 when the liquid has reached the desired low level will, due to its weight, cause the valve 55 to close. Thereafter the slow leak line connection 110 permits the higher pressure in the trap chamber 14 to be lowered and equalized with the sub-atmospheric pressure in the tank B, and the liquid through the line 15 again enters the trap compartment.

The provision of a variable orifice in the equalizing line 110 is highly desirable to meet all existing pressure and vacuum conditions. When a low actuating pressure is used to discharge the fluid from the trap it has been

found that the variable leak valve 112 should be opened to a considerable extent, without the serious loss of actuating pressure passing through the equalizing line 110 into the vacuum tank B. In case a high actuated pressure is used, the variable leak valve is substantially closed, thus preventing the excessive loss of actuating pressure through the equalizing line, and correspondingly preventing the lowering of vacuum in the receiver or tank B. Thus, a flexibility of control is provided which is a considerable improvement over the fixed leak which is disclosed in the co-pending application above mentioned.

The improved pressure controlling valve and float mechanism enables the valve to be actuated with a sort of snap action. This is due to the free play of the float arm between the chisel edges facing the upper and lower ends of the opening 60 of the stirrup 62. The rising of the float arm with the liquid enables the float arm, when the liquid has reached a predetermined maximum level, to engage against the upper chisel edge of the stirrup 62, quickly snapping the valve 55 open to admit pressure to the trap compartment for discharge of liquid therefrom. The valve 55 remains open during discharge of liquid from the trap, due to the fact that the counterweight holds it open, until the valve arm 64 has lowered to the extent where it will contact the lower chisel edge facing the opening 63 of the stirrup 62, and gravitating downwardly will cause the valve 55 to be snapped shut. The fact that the fulcrum point 88 may be variably adjusted with respect to the stirrup 62 of the valve mechanism permits the device to operate efficiently under various actuating pressures. If this were not the case the float mechanism might be able to close the pressure control valve for a high actuating pressure but not be able to reopen it again due to insufficient leverage force under buoyancy. Also for a low actuating pressure the float mechanism if not adjustable might be able to open the valve, but the weight of the float and float arm might not be sufficient to balance the counterweight and close the valve.

When the actuating pressure in the line 27 is low, the adjustable screw 95 is adjusted out of the cap 82 to its farthest extent, or to the extent desired. This decreases the leverage of the float arm 64 in its actuation upon the valve mechanism, to the extent required for a low actuating pressure. Should the actuating pressure in the line 27 be high, it will then be necessary to adjust the screw 95 into the cap 82, in order to increase the leverage of the float arm. It is to be noted that there is a lower triangular portion on the float arm 64 adjacent its fulcrum connection, the lower edge 115 of which is horizontally positioned when the float arm 64 is lowered to

130

the lowest extent desired. This edge 115 cooperates on the lower chisel edge of the stirrup 62, as shown in Figure 1, and maintains the float in the same horizontal plane, regardless of the adjustment of the fulcrum for a high or low actuating pressure.

In the provision of the counterweight mechanism, which balances or partially balances the valve parts and float parts, the necessity of compensating for the weight of these parts thru the adjusting screw 95 is eliminated. Also the counterbalancing weight increases the available or effective buoyancy of the float mechanism due to the fact that it is unnecessary for the float to support the entire weight of the valve mechanism during actuation.

Various changes in the shape, size, and arrangement of parts may be made to the form of invention herein shown and described, without departing from the spirit of the invention or the scope of the claims.

I claim:

1. In a liquid extractor of the class described a casing having a chamber therein, check valve controlled inlet and outlet means for regulating admission and extraction of liquids with respect to the chamber, a variably regulatable low pressure equalizing connection with the casing chamber, a high pressure inlet control valve for the casing placed so that the pressure is exerted thereon to normally maintain the valve closed, float means in the casing having an operative connection with the pressure inlet valve for opening the latter at a predetermined high level of liquid in the casing to admit air or gas for driving the liquid from the chamber, said float means having a pivotal mounting in said casing spaced from the operative connection of the float means with said valve, and means for moving the effective pivot axis of said float means towards or away from the operative connection of the float means with said valve to increase or decrease the leverage action of the float means upon said valve.

2. In a fluid extractor of the class described the combination of a trap casing having a liquid trap chamber therein, check valve controlled inlet and outlet connections for the casing, a pressure control valve for admitting discharge pressures into the casing for discharging liquid therefrom, a float arm having a float therein, a movable member to which the arm is fixedly pivoted, means connected with the pressure control valve having an elongated opening through which the float arm extends at a point between the float and its pivot connection with said member whereby the float arm at a predetermined high level of liquid will cause an opening of the valve and at a predetermined low level of liquid will cause a closing of the valve, and means for moving said member towards or away from the opening through which said

float arm extends whereby to increase or decrease the effective leverage action of the float arm upon said pressure control valve.

3. In a fluid extractor of the class described the combination of a trap casing having a liquid trap chamber therein, check valve controlled inlet and outlet connections for the casing, a high pressure control valve for admitting discharge pressures into the casing for discharging liquid therefrom, a float arm having a float therein and having a pivot connection in the casing, a member connected with the pressure control valve having an elongated opening through which the float arm extends at a point between the float and its pivot connection whereby the float arm at a predetermined high level of liquid will cause an opening of the valve and at a predetermined low level of liquid will cause a closing of the valve, means for adjusting the pivot of the float arm towards or away from the member connected with said float arm whereby to increase or decrease the effective leverage action of the float arm upon said pressure control valve, and counterweight means acting on the pressure control valve normally tending to open the same against the dead weight of the pressure control valve.

4. In a fluid extractor of the class described a trap chamber having inlet and outlet connections for admission and exit of liquid with respect thereto, check valves for said inlet and outlet connections for admitting and permitting discharge of liquid with respect to the trap casing, a discharge pressure control valve for the casing, float means including a float arm having a loose operative connection with said pressure control valve for snapping the same open at a predetermined high level of liquid in the casing and snapping the same closed at a predetermined low level of liquid in the casing, means establishing a pivot mounting for the float arm in the casing and at a point spaced from the connection of the float arm with said pressure control valve, means adjustable from exteriorly of the casing for variably positioning the effective pivot axis of the float arm towards or away from the connection of the float arm with said pressure control valve, said float arm and pressure control valve connection with the float arm being constructed to permit the float arm pivot axis to be regulated with increased or decreased leverage action on the pressure control valve without destroying the effective level of the float arm with respect to the trap casing.

5. In a trap of the class described the combination of a casing having check valve controlled liquid inlets and outlets, a high pressure admission control valve mechanism for the casing, a lever pivoted between its ends upon the casing having a movable connection at one end directly with said control

valve mechanism, a sliding counterweight on the other end of the said lever at the opposite side of its pivot with respect to its connection with said valve, means to adjustably clamp the counterweight at a desired location along the lever to balance the weight of the parts of the valve, and float means directly connected with said valve mechanism independent of any connection with said lever for opening and closing the valve.

6. In a trap of the class described the combination of a casing having check valve control liquid inlets and outlets, a high pressure admission control valve for the casing, counter balance means normally tending to open the valve and balance the weight of the parts thereof, fluid actuated float means in the casing for opening and closing said valve, and means for increasing and decreasing the forced action of the float means upon said valve proportionate to the pressure acting against said valve.

7. In a device of the class described the combination of a casing having a chamber therein, a pressure chest, a valve structure for controlling flow of the pressure medium between the casing and the pressure chest, float means for opening and closing the valve structure including a float arm having a movable connection intermediate its ends with said valve structure, means establishing a pivot mounting for the float arm in the casing, means adjustable from exteriorly of the casing for variably positioning the effective pivot axis of the float arm towards or away from the movable connection of the float arm with the valve structure, said float arm having a substantially straight edge at its connection with the valve structure which is substantially positioned parallel with the line along which the pivot axis of the float arm may be adjusted so as to permit the float arm to be moved to increase or decrease the leverage action of it upon the valve structure without destroying uniformity of level of the float portion of the arm.

LYLE W. BROWNE.
